UNITED STATES PATENT OFFICE.

THOMAS FRANCIS BURKE, OF PERTH AMBOY, NEW JERSEY.

ASH-CAN.

SPECIFICATION forming part of Letters Patent No. 634,551, dated October 10, 1899.

Application filed February 28, 1899. Serial No. 707,139. (No model.)

To all whom it may concern:

Be it known that I, THOMAS FRANCIS BURKE, a citizen of the United States, residing at Perth Amboy, in the county of Middlesex and State of New Jersey, have invented certain new and useful Improvements in Ash-Cans, of which the following is a full and complete specification, such as will enable those skilled in the art to which it appertains to make and use the same.

This invention relates to ash-cans; and the object thereof is to provide improved means for rolling, turning, or otherwise moving a can of this class from point to point while holding the can in an inclined position without grasping the top of the can with the hands and moving the hands around said top.

The invention is fully disclosed in the following specification, of which the accompanying drawings form a part, in which the separate parts of my improvement are designated by the same numerals of reference in each of the views, and in which—

Figure 1 is a central vertical section of an ash-can provided with my improvement, and Fig. 2 a plan view thereof.

In the practice of my invention I provide an ash-can 5 of the usual form and composed of any desired material, and said can is provided adjacent to the top thereof with two outwardly-directed flanges or rims 6, between which is loosely placed a ring 7, which is provided at the opposite sides with handles 8.

In the construction shown in the drawings the flanges or rims 6 are composed of angle-iron and are bolted to a band 9, which is bolted or riveted to the can 5, as shown at 10; but my invention is not limited to the means herein described for connecting the flanges or rims 6 with the can, the only object in this connection being to provide an annular trough or groove adapted to receive the ring 7.

In the construction shown in Fig. 1 the ring 7 is cylindrical in cross-section; but said ring itself may be of any desired shape in cross-section, and the handles 8 may be formed integrally therewith or may be connected therewith in any desired manner.

In practice the handles 8 are grasped by the hands and the can is turned into an inclined position, and the said can is free to turn in the ring 7, and by holding the can in

an inclined position and applying sufficient force or pressure to both of the handles 8 in the same direction the can may be rolled from point to point without grasping the top edge thereof and moving the hands thereon, as heretofore.

In handling ash-cans or moving the same from point to point it is customary to grasp the top edge or rim with the hands and to incline the can, and then by moving the hands around the top edge or rim to roll the can on the edge of the bottom thereof to the desired point. This is a difficult operation and frequently results in injuring the hands; but with my improvement by grasping the handles 8 and holding the same firmly and inclining the can and applying sufficient force in the direction in which it is desired to move the can may be freely rolled from point to point, it being understood that the handles 8 and ring 7 do not move, the can turning freely in said ring.

My improvement is simple in construction and operation and perfectly adapted to accomplish the result for which it is intended, and it will be apparent that changes in and modifications of the construction described may be made without departing from the spirit of my invention or sacrificing its advantages.

Having fully described my invention, I claim as new and desire to secure by Letters Patent—

1. An ash-can provided with an annular groove or space near the top thereof, and a ring or band mounted loosely therein, and in which the can is adapted to turn, said ring or band being provided with handles at its opposite sides, substantially as shown and described.

2. The combination with an ash-can provided with annular flanges or rims near the top thereof, which form an annular groove or space, of a ring or band mounted in said annular groove or space and in which the can is adapted to turn, said ring or band being provided at its opposite sides with handles, substantially as shown and described.

3. The combination with an ash-can, of a ring or band mounted thereon at or near the top thereof in which the can is adapted to turn, and said ring or band being provided on its

opposite sides with handles, substantially as shown and described.

4. An ash-can provided with a ring or band loosely mounted thereon, at or near the top thereof, and in which said can is free to turn, said ring or band being provided at its opposite sides with handles, substantially as shown and described.

In testimony that I claim the foregoing as my invention I have signed my name, in presence of the subscribing witnesses, this 25th day of February, 1899.

THOMAS FRANCIS BURKE.
